COMBINED COIN COUNTING AND WRAPPING AND MEASURING DEVICE

Edward S. Oltarzewski, Bayonne, N. J.

Application May 4, 1956, Serial No. 582,873

2 Claims. (Cl. 53—254)

This invention relates generally to measuring apparatus and the primary object of invention is most particularly concerned with apparatus incorporating means for coin counting and wrapping as well as means for making both angular and linear measurements.

A specific object of invention is to provide in apparatus of the character involved a pair of juxta-positionable body members pivotally connected at adjacent edge portions, said body members including on mating surface portions cooperating semi-cylindrical blind bore portions defining a cylindrical blind bore when the mating surfaces are juxtaposed for receiving coins therein, as well as indicia means linearly disposed on the mating surface portions adjacent the semi-cylindrical blind bore portions for measuring a predetermined quantity of coins of different denominations.

A further object of the invention in conformance with that set forth above is to provide in apparatus of the character set forth in which the semi-cylindrical blind bore portions terminate in semi-truncated conical grooves opening into adjacent ends of the body members for defining an outwardly opening funnel portion in communication with the blind bore portion for facilitating the insertion of coins in the device.

Another object of invention in conformance with those set forth above is to provide in apparatus of the character set forth indicia means along an outer edge portion of a surface portion of one of the body members for measuring linear distances and including protractor means on the device for angular measurements wherein said protractor has a base portion disposed in right angular relationship to the aforementioned edge portion whereby a square is provided.

A further object of invention in conformance with those set forth above is to provide apparatus of the character set forth which is readily and economically manufactured, easily and efficiently used, and highly practical and satisfactory for the purposes intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the novel apparatus, showing in phantom lines the manner in which a coin wrapper is utilized therewith;

Figure 2 is a perspective view of the novel apparatus in an alternate position, showing the interior of the mating body members thereof;

Figure 3 is a sectional view taken substantially on line 3—3 of Figure 1;

Figure 4 is a sectional view taken substantially on line 4—4 of Figure 3; and

Figure 5 is a sectional view taken substantially on line 5—5 of Figure 3.

2

Referring to the drawings, the novel measuring apparatus is indicated generally at 10 and comprises a substantially rectangularly conformed member 12 including juxta-positionable body members 14 and 16 which have 5 suitably secured at the rear end portion 18 thereof, suitable hinge means 20, the leaf portions 22 and 24 thereof being recessed in suitable portions on the end portion 18 if so desired.

As most clearly seen in Figure 2 the body members 14 and 16 include inner mating surface portions 26 and 28, respectively, each of the mating surface portions having extending therethrough a semi-cylindrical blind bore portion 30 and 32, respectively, which respectively include semi-circular end portions 34 and 36, said semi-cylindrical blind bore portions cooperating when in juxtaposition as seen in Figure 1 define a longitudinally extending blind bore portion 38 within the member 12. The semi-cylindrical blind bore portions 30 and 32 each terminating in an outwardly opening semi-conical truncated groove portions 40 and 42, respectively, which open toward the end portions 44 and 46 of the respective body members 14 and 16, and which cooperate when disposed in the position seen in Figure 1 to form an outwardly opening funnel portion, facilitating the insertion of coins in the device.

The inner or mating surface portions 26 and 28 each include in linear alignment with the semi-cylindrical blind bore portions indicia scales 48 and 50, and 52 and 54, which are graduated to indicate the number of coins 30 of various denominations which may constitute a predetermined given amount of money. Thus observing Figure 2, it will be noted that when utilizing the device to roll pennies the graduations go up to fifty constituting the number of pennies generally placed in a single roll, 35 when rolling nickles there has been indicated that forty nickles would constitute a roll being formed, likewise when rolling dimes fifty dimes would constitute the number placed in a single roll and when rolling quarters forty quarters would be incorporated in a single roll. 40 It is obvious that any of the intermediate graduations may be utilized for the purpose of counting intermediate numbers of coins placed in the device.

The apparatus when being used for forming rolls of coins held in the position shown in Figure 1 whereafter a given amount or number of coins is placed within the blind bore portion 38 of the device, the body members being separated readily for the purpose of determining the correct count obtained, thereafter the coin wrapper 45 is placed in overlying relationship to the coins when the device is in the position shown in Figure 2, it being noted that the printing side of the coin wrapper faces upwardly at this time, then the body member 16 is again urged into the position shown in Figure 1 whereafter the apparatus is inverted so that the member 16 becomes the lowermost body member and then the wrapper together with the previously counted coins are slid longitudinally from the apparatus and manually rolled in a conventional manner.

60 Incorporated on the outer surface portion 54 of the body member 14, for example, adjacent the external linear edge 56 thereof is a linear measuring scale which permits the straight edge 56 of the apparatus to be used as a ruler.

65 Secured by means of suitable fastening elements 58 is a protractor member 60 which incorporates along a semi-circular edge portion thereof, designated 62, a conventional scale for making angular measurements. The base portion 65 of the protractor member is disposed at right angles to the linear edge 56 of the apparatus thus providing a square which may be used for various purposes. The side portion 66 of the protractor is in sub-

stantially planar alignment with the surface portion 54 of the body member 14 and thus provides an abutment along the upper edge 68 of the mating surface portion 26 of the body member 14 for substantially positioning an edge portion of the coin wrapper normal to the semi-cylindrical blind bore portion of the body member 14.

The device may be constructed from any suitable material such as aluminum, plastic, etc. but it is to be understood that linear measuring scales may be incorporated on other portions of the device, for example, along the lower edge 70 of the body member 16 whereby the linear measuring scale may be doubled.

Operation of the apparatus as heretofore described is readily apparent, and there has been disclosed measuring apparatus which fully conforms with the objects of invention heretofore set forth.

Various positional directional terms such as upper, lower, etc. are utilized herein to have only a relative connotation to aid in describing the device and it is not intended to require any particular orientation with respect to any external elements.

The foregoing is illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the appended claims.

What is claimed is:

1. Measuring apparatus comprising an elongated rectangularly conformed member including a pair of juxtaposable body members having an external rectangular configuration, hinge means extending between adjacent transverse end portions of the body members providing pivotally related juxtaposable mating surface portions between said body members, each of said mating surface portions including longitudinally extending overlying semi-cylindrical blind bore portions defining a longitudinal blind bore opening into adjacent end portions of the body members opposite the hinge means when the body members are juxtaposed, coin-counting indicia means linearly disposed on the mating surface portions of the body members in a linear alignment along the semi-cylindrical blind bore portion, one of said body members including an external straight edge portion opposite the mating surface portion thereof, linear scale means con-

tained on an outer surface portion of the one body member along the straight edge portion, and a protractor member mounted on said one body member, said protractor member including an angular scale along a semi-circular edge portion thereof, said protractor member including a linear base edge portion disposed at right angles to the straight edge portion of said one body member for providing a square on the apparatus.

2. Measuring apparatus comprising an elongated rectangularly conformed member including a pair of juxtaposable body members having an external rectangular configuration, hinge means extending between adjacent transverse end portions of the body members providing pivotally related juxtaposable mating surface portions between said body members, each of said mating surface portions including longitudinally extending overlying semi-cylindrical blind bore portions defining a longitudinal blind bore opening into adjacent end portions of the body members opposite the hinge means when the body members are juxtaposed, coin-counting indicia means linearly disposed on the mating surface portions of the body members in a linear alignment along the semi-cylindrical blind bore portion, one of said body members including an external straight edge portion opposite the mating surface portion thereof, linear scale means contained on an outer surface portion of the one body member along the straight edge portion, and a protractor member mounted on said one body member, said protractor member including an angular scale along a semi-circular edge portion thereof, said protractor member including a linear base edge portion disposed at right angles to the straight edge portion of said one body member for providing a square on the apparatus, said protractor including a surface portion disposed in planar alignment with the outer surface portion of the one body member, said surface portion of the protractor being disposed normal to the mating surface portion of the one body member and comprising an abutment portion engageable with an edge portion of a coin wrapper inserted between the mating surface portions of the body members.
